UNITED STATES PATENT OFFICE.

HOWARD G. WASHBURN, LAFAYETTE G. JOHNSON, AND JOSEPH R. THILL, OF FLAT RIVER, MISSOURI, ASSIGNEES TO AMERICAN MANGANESE STEEL COMPANY, OF CHICAGO, ILLINOIS, A CORPORATION OF MAINE.

TOOTHED CUTTER LIP.

Application filed May 28, 1921. Serial No. 473,370.

To all whom it may concern:

Be it known that we, HOWARD G. WASHBURN, LAFAYETTE G. JOHNSON, and JOSEPH R. THILL, citizens of the United States, residing at Flat River, in the State of Missouri, have invented certain new and useful Improvements in Toothed Cutter Lips, of which the following is a specification.

10 Our invention relates to digging buckets or dippers, and has particular reference to a cutting lip therefor.

The invention relates to a cutting lip for excavating machines, which may be used 15 with such excavating apparatus as steam shovel dippers, ladder dredge buckets, clam shell buckets and the like, and where reference is made hereinafter to digging buckets all of the above are to be understood as included broadly in this term.

An object of our invention is to provide a cutter lip for digging buckets which is formed from a single casting and in which there are formed digging teeth, or points, 25 with reinforcing lips and a web construction between the points for the purpose of strengthening the lip.

Another object of our invention is to provide a cutter lip for digging buckets having digging teeth formed therein.

A further object of our invention is to provide a tooth digging or cutting lip, of the described character, in which the teeth are connected by webs for eliminating 35 breakage.

A still further object of the invention is to provide a cutter lip having digging teeth or points integrally formed and in which there is used a web construction for connecting the teeth to aid in distributing strain 40 over the lip whenever obstructions are encountered in digging.

A still further object is to improve cutting lips for digging buckets for successful commercial use.

The above and other objects will be apparent from the following specification and drawings, and will be particularly pointed out in the appended claims.

50 In the drawings:

Fig. 1 is a top plan view of the preferred embodiment of the invention.

Fig. 2 is a vertical section taken on line 2-2 of Fig. 1.

Fig. 3 is a rear end view of the arrangement of Fig. 1.

Fig. 4 is a transverse section on line 4-4 of Fig. 1.

Fig. 5 is a transverse section on line 5-5 of Fig. 1.

Fig. 6 is a side elevation looking at the left-hand end of Fig. 1.

Fig. 7 is an enlarged fragmentary view showing the preferred construction of bolt holes, and Fig. 8 is a section taken on line 8-8 of Fig. 1.

The reference character 10 designates generally the toothed cutter lip of our invention. As shown, the lip comprises an upper surface 11 which is secured to a digging bucket of any well known form and shape. Bolt holes 12 are provided through which bolts, rivets or similar means may be employed to fasten the lip to a bucket. At each side of the lip there are 75 upstanding side portion 13-14 for preventing lateral displacement of the lip when secured to a bucket and wear in service. Forwardly of the flat surface 11 is what may be termed the digging portion of the 80 lip. Referring to Figs. 4, 5 and 6 of the drawing, it will be noted that the digging portion is inclined downwardly, forming a cutting edge. Extending longitudinally of the lip,—that is, in the direction of the 85 digging movement,—there are formed a plurality of ribs 15 which are cast with the lip, the forward ends of which ribs are pointed as at 16 in Fig. 4. The pointed portions of the ribs are in effect digging 90 teeth or points.

For strengthening the digging portion of the lip webs 17 are cast connecting the several ribs 15 and side portions of the lip. The front edges of the webs are sharpened 95 or pointed as at 18 in Fig. 5 so that the whole digging front of the lip is pointed or sharpened for purposes well understood.

In Fig. 7 there is disclosed countersunk and counterbored holes for the reception of 100 rivets or other attaching means. We prefer to employ bolt holes of this character so that the lip may be securely fastened to the dipper body and so that the rivets or other

attaching means will not project beyond the outer or wearing surfaces of the ribs.

Our construction improves digging lips for use with digging buckets by casting the digging point or teeth integrally with the lip, and by providing connecting webs between the teeth, the lip is strengthened and the likelihood of a tooth being broken in service is eliminated. Furthermore, by relieving the cutting edge,—that is, by the novel point and web construction of the invention, as shown in the drawings,—digging is made easier than if a plain or straight lip were used. Furthermore, by provision of the longitudinally extending ribs, the front ends of which form the digging teeth, the lip is strengthened and reinforced considerably. Furthermore, digging strains are distributed throughout the whole casting.

While we have described more or less precisely the details of construction of our invention, we do not wish to be understood as limiting ourselves thereto, as we contemplate changes in form and the proportion of parts and the substitution of equivalents as circumstances may suggest or render expedient, without departing from the spirit of our invention.

30 We claim:

1. A one-piece cutter lip for digging buckets having a plurality of longitudinally

extending ribs spaced apart on its under side and terminating in pointed digging teeth at their forward ends.

35

2. A one-piece cutter lip for digging buckets having a plurality of longitudinally extending ribs spaced apart on its under side and terminating in downwardly inclined digging teeth at their forward ends. 40

3. A one-piece cutter lip for digging buckets having upstanding side portions and a plurality of ribs spaced apart between said side portions and parallel therewith, and terminating in digging teeth at their 45 forward ends.

4. A one-piece cutter lip for digging buckets having a plurality of longitudinal ribs spaced apart and connected by webs to form a substantially fluted underside, and 50 said ribs terminating in digger points at their forward ends.

5. A one-piece cutter lip for digging buckets having a plurality of longitudinal ribs spaced apart and connected by webs 55 and forming a fluted underside, said ribs being pointed to form digger points at their forward ends, and said webs being sharpened at their forward ends.

Signed at Flat River, Missouri, this 28th 60 day of April, A. D. 1921.

HOWARD G. WASHBURN.
LAFAYETTE G. JOHNSON.
JOSEPH R. THILL.
